CLAIM

The ornamental design for a display screen or portion thereof with graphical user interface for publishing a report with an abstraction tool, as shown and described.

DESCRIPTION

FIG. 1 is a front view of a first image in a sequence of a display screen or portion thereof with graphical user interface for publishing a report with an abstraction tool showing our new design;

FIG. 2 is a front view of a second image thereof; and, FIG. 3 is a front view of a third image thereof.

The outermost broken lined rectangles indicate a boundary of a display screen or a portion thereof and form no part of the claimed design. The broken lined text and characters form no part of the claimed design.

The appearance of the animated images sequentially transition from FIG. 1 to FIG. 3. The process or period in which one image transitions to another forms no part of the claimed design.
